UNITED STATES PATENT OFFICE.

WALLACE W. BUGH, OF NORTH TONAWANDA, NEW YORK.

SPARK-PLUG.

1,315,945.

Specification of Letters Patent. Patented Sept. 16, 1919.

Application filed October 9, 1918. Serial No. 257,494.

To all whom it may concern:

Be it known that I, WALLACE W. BUGH, a citizen of the United States, residing at North Tonawanda, in the county of Niagara 5 and State of New York, have invented new and useful Improvements in Spark-Plugs, of which the following is a specification.

This invention relates to spark plugs especially designed for use in connection with 10 internal combustion engines.

One object of the present invention is the provision of a spark plug in which the coupling is fastened on the core in such manner as to render the union airtight.

15 Another object of the invention is the provision in a spark plug, of means, preferably resilient, for holding a shoulder on an electrode in airtight engagement with a complementary abutment of the core to afford an airtight engagement independent of expansion or contraction of the electrode.

Another object of the invention is to produce a spark plug which is practically airtight and leak-proof and which can not be 25 tampered with by the owner of the plug but which at the same time may be readily cleaned as far as the power and ground electrodes or sparking points are concerned. One of the great disadvantages of the ordinary

30 spark plugs now in common use is that it consists of a number of parts which may be easily separated from each other by the average owner of a motor vehicle, with the result that the parts are not properly re- 35 assembled by such person not skilled in the art, the result being an inoperative or at the best an inefficient and unsatisfactory plug. The present invention overcomes that difficulty approximated by the construction here- 40 in shown and described.

With the above and other objects in view, the invention consists in the novel construction, combination and arrangement of parts herein fully described, illustrated and 45 claimed.

Figure 1 of the accompanying drawings represents a central longitudinal section through the improved spark plug.

Fig. 2 is a similar view showing the spark 50 plug in a modified form.

The present invention relates mainly to the core and the attachment thereof together with the central or power electrode, as an enclosing metallic shell and ground electrode 55 of any approved formation may be employed in connection with the structure illustrated

in Figs. 1 and 2 of the accompanying drawing.

Referring to the drawings 1 designates the core of a spark plug, said core being ordinarily formed of porcelain, or other appropriate insulating material. 2 designates the power electrode which passes centrally and longitudinally through the core 1, the bore 3 in the core being of just sufficient size to admit of the insertion of the power electrode therethrough and the inner extremity of the bore 3 being flared or enlarged in conical formation as shown at 4. The power electrode 3 is formed with an enlargement or collar 5 having a cone-shaped face 6 which is adapted to fit snugly and tightly against the flared or cone face 4 of the core 1. A tight joint is thus formed between the power electrode and the inner end of the core. The core is provided with the usual enlargement or circumferential flange 7 adapting it to be firmly and positively seated in the surrounding shell not shown in the drawings. The core is also formed at the outer end thereof with an enlarged head or collar 8 which forms an integral part of the core and forms a part of the means by which the catch hereinafter referred to is fastened to the core.

In connection with the outer end of the core 1, I employ a metal cap 9 of cylindrical or disk formation having its peripheral edge threaded to be engaged by an internally threaded union or coupling member 11 90 which surrounds the flange or head 8 and has its inner edge swaged to form an inwardly extending annular lip 12 which underlies and bears firmly against the inner surface of the head 8. An air-tight gasket 95 13 preferably of some hard compressible material is interposed between the cap 9 and the outer end of the core 1 being held under compression by the inwardly swaged annular lip 12, thus forming a leak-proof 100 air-tight joint at this point.

Extending upwardly from the cap 9 is a sleeve-like extension or elongated cooling sleeve 14 which also surrounds the power electrode 2 as shown in Fig. 1. A part of 105 the sleeve-like extension 14 is enlarged as shown at 15 and such enlarged portion is formed with an annular groove or seat 16 designed to receive the terminal of the ignition feed wire used in conjunction with 110 the plug. The extreme outer end of the sleeve-like extension 14 is enlarged as shown

to form a hollow chamber 18 in which is arranged a coiled compression spring 19 which surrounds the outer end portion of the electrode 2, bearing at one end against the inner 5 wall 20 of the chamber 18 and bearing at its outer end against a collar or shoulder 21 on the electrode 2. The spring 19 operates to hold the extremities 5 and 6 in air-tight contact with each other.

10 By means of the construction hereinabove described and shown in Fig. 1, a fixed air-tight and leak-proof connection is established between the power electrode and the core and also between said electrode and the 15 cap to which the terminal of the circuit wire is attached. The parts can not be separated, thereby rendering the plug leak-proof and adapted for long efficient service.

If desired the plug as a whole may be 20 made relatively shorter by resorting to the construction and arrangement illustrated in Fig. 2, in which the cap indicated at 9' is formed with an internal chamber 22 to receive the spring 19' which holds the shoulders 25 of the core 1 and the electrode 2 in firm engagement with each other. The union or coupling 11' secures the cap 9' to the core 1 in the same manner as described in connection with Fig. 1, and also serves to compress 30 the gasket 13' which is interposed between said cap 9' and the adjacent end of the core 1. The cap 9' is formed with a socket 23 in the end thereof to receive the terminal of the circuit or current wire which 35 furnishes current to the spark plug electrode. It is, of course, to be understood that any form of outer shell or casing and ground electrode may be used in conjunction with the structure herein shown and described 40 for the purpose of grounding the current passing through the power electrode 2.

Having thus described the invention, what is claimed as new, is:—

45 1. In a spark plug, the combination of a core having a longitudinal bore therethrough, a power electrode passing through

said core and having a beveled shoulder which presses against a corresponding beveled shoulder at the inner end of said core, 50 a cap at the outer end of said core, a union connecting said cap and core, and a spring engaging said electrode and cap and serving to maintain air-tight contact between the shoulders of the core and electrode, said cap 55 being formed with an air-tight chamber inclosing said spring.

2. In a spark plug, the combination of a core, a power electrode extending longitudinally therethrough, contacting air-tight 60 shoulders on said electrode and core, a spring for holding said shoulders in engagement with each other, a cap inclosing said spring and a portion of said electrode, a union connecting said cap and core, and an air-tight 65 gasket interposed between said cap and core.

3. A spark plug from which air is excluded comprising a core, an electrode exposed at the inner end of the core, and a cap fastened in air-tight manner on the 70 outer portion of the core and entirely inclosing the electrode and having an elongated cooling sleeve closed at its outer end.

4. The combination in a spark plug, of a core, an electrode extending longitudinally 75 therethrough, portions on said core and electrode affording an airtight joint, resilient means for holding said portions in engagement, and a cap inclosing said resilient means and connected in airtight manner 80 with the core.

5. In a spark plug, the combination of a core, an electrode extending longitudinally therethrough, contacting airtight shoulders on said core and electrode, a cap connected 85 to the core, an elongated cooling sleeve on said cap, and a spring for holding said shoulders in engagement with each other, said cap and sleeve forming an inclosure for the spring and a portion of the electrode. 90

In testimony whereof I affix my signature,

WALLACE W. BUGH.
